UNITED STATES PATENT OFFICE

BENJAMIN GILOWITZ, OF NEW YORK, N. Y.

SHOE HEEL

Application filed January 9, 1930. Serial No. 419,627.

The invention relates to composite heels and aims to provide a new and improved heel construction having the advantages of a rubber heel but formed to a large extent 5 from compressed paper or other relatively cheap material for inexpensive manufacture.

A further object is to provide a simple and advantageous method for constructing the heel.

10 With the foregoing in view, the invention resides in the novel subject matter herein-after described and claimed, description being accomplished by reference to the accompanying drawings.

15 Fig. 1 is a perspective view showing one form of heel constructed in accordance with my invention.

Fig. 1^a is a top plan view showing a still further modification.

20 Fig. 2 is a perspective view showing the three elements of the heel separated from each other.

Fig. 2^a is a side elevation of the heel shown in Fig. 1^a.

25 Fig. 3 is a longitudinal sectional view on line 3—3 of Fig. 1.

Fig. 4 is a transverse sectional view on line 4—4 of Fig. 1.

In the form of construction shown in Figs. 30 1 to 4, a body 10 of solid inelastic material, such as compressed paper, is provided, said body being recessed from top to bottom.

The recesses are in the form of shallow vertical grooves 11 and 11^a, the grooves 11^a 35 being disposed at the front corners of the body and being of greater dimension trans-

versely of the heel than the grooves 11. A rubber lift 12 is secured against the lower

40 side of the body 10 and a rubber layer 13 is secured against the upper side of said body.

Vertical necks 14 and 14^a, formed of rubber, are integrally joined to the lift 12 and the layer 13, and are snugly secured in the 45 grooves 11 and 11^a respectively. The necks

14^a being larger and stronger, afford greater strength at the front corners of the heel.

By the construction above described, with a minimum of rubber, a heel is provided having the advantages of a rubber heel and yet 50 constructed to a large extent from relatively inexpensive material, such as compressed paper. Moreover, the construction is such as to give an unusually attractive appearance to the heel, rendering it particularly adaptable for sport shoes. 55

Whenever the lift 12 is worn out, it may be detached from the body 10 by cutting the necks 14 and 14^a at their juncture with the lift. Then, a new lift may be secured to the 60 lower side of the body 10.

To insure more thorough anchorage of the rubber layer 13 to the shoe, it may be recessed at 15 upon its upper side, for cement-receiving purposes. 65

In Figs. 1^a and 2^a, a heel is shown rather similar to the one disclosed in Figs. 1 to 4. This heel embodies a body 10^a of solid incompressible material, such as hard pressed paper, the peripheral edge of said body being provided with relatively deep and narrow vertical grooves 11^a. A rubber heel lift 12^a is secured to the lower side of the body 10^a, a thin top layer 13^a of rubber is provided 70 upon the upper side of said body, and vertical tongues 14^a, formed from rubber, completely fill the grooves 11^a, said tongues being integrally joined at their ends to the lift 12^a and the top layer 13^a. This top layer is provided with a recess 15^a for the same purpose 75 as the recess 15.

While the details disclosed are preferably followed, variations may be made within the scope of the invention as claimed. While nail holes are shown in Fig. 3, the heel may be made without them if desired, allowing a person attaching the heel to drive the nails anywhere desired, counter-sinking them until their heads abut the body 10 or 10^a. 80

I claim:—

A composite heel comprising a body of solid non-resilient material having vertical grooves in its peripheral edge from its upper to its lower side, a rubber heel lift secured to the lower side of said body, a relatively thin layer of rubber secured to the upper side of said body, and a plurality of vertical rubber necks snugly received in said grooves and integrally joined to said lift and said layer.

In testimony whereof I have hereunto affixed my signature.

BENJAMIN GILOWITZ.
